UNITED STATES PATENT OFFICE

ELMER G. GARTIN, OF CLAREMONT, NEW HAMPSHIRE, ASSIGNEE TO SULLIVAN MACHINERY COMPANY, A CORPORATION OF MASSACHUSETTS

DRILLING MECHANISM

Application filed December 13, 1923. Serial No. 680,523.

My invention relates to drilling mechanisms.

An object of my invention is to provide an improved drilling mechanism and more particularly a rock drilling mechanism having improved cleansing fluid supply means therefor. Another object of my invention is to provide an improved drilling mechanism of the pressure fluid percussive type especially adapted for rock drilling purposes whereby improved means for supplying cleansing fluid to the drill steel are provided. A still further object of my invention is to provide an improved pressure fluid percussive tool provided with a hammer piston adapted to actuate a drill steel whereby improved means are provided for supplementing the cleansing fluid supply to the drill steel for removing the cuttings from the drill hole. These and other objects and advantages of my invention will, however, hereinafter more fully appear.

In the accompanying drawings I have shown for purposes of illustration one form which my invention may assume in practice.

In these drawings,—

Fig. 1 is a central longitudinal vertical sectional view through a drilling mechanism in which one form of my improved mechanism is incorporated, the view being partially in side elevation.

Fig. 2 is a view similar to that shown in Fig. 1, with parts assuming different positions, the forward end of the drilling mechanism being broken away to facilitate illustration.

In this illustrative embodiment of my invention I have shown a drilling mechanism of the pressure fluid percussive type, generally indicated by 1, comprising a cylinder 2 having a bore 3 in which a piston 4 is reciprocable and adapted to percussively actuate a drill steel 5 carried in a chuck 6 suitably arranged within the front end of the drill. The ends of the bore 3 are closed by suitable head members 7 and 8, the head 7 being held in the desired assembled relation in any well known manner, while the head 8 is forged integral with the cylinder. Herein, pressure fluid is adapted to be distributed to the oppo-

site ends of the cylinder 2 by way of distribution passages 9 and 10 leading to the opposite ends of the cylinder bore 3, these passages 9 and 10 being adapted to be connected alternately to supply and exhaust by means of a suitable valve mechanism, generally designated 11, in which a valve of the multiple spool type (not shown) is adapted to be reciprocated under the control of longitudinally spaced reverse or throw passages 12 and 13 controlled by the piston leading from opposite ends of the valve to the cylinder bore in the usual manner. Pressure fluid is adapted to be admitted to the valve mechanism through a pipe connection 14 from any suitable source of supply under the control of a throttle valve mechanism 15 suitably arranged within the back head 7.

In my improved construction it will be observed that a plurality of longitudinally extending concentric tubular members 16 and 17 are rigidly held in the desired relation by means of a gland plug 18 suitably threaded into the rear head 7. These tubes 16 and 17 are provided at the rear ends with flanges or heads 19 and 20 held in spaced relation by means of rubber washers or packings 21, in a well known manner. Herein, the air tube 16 extends longitudinally, terminating at its free end in a bore 22 formed in the front end of the piston 4 and which has a running fit therewith. This bore 22 in turn communicates with an enlarged annular chamber 23 formed contiguous to the shank of the drill steel to which pressure fluid is constantly supplied from an annular chamber 24 at the rear end of the tube communicating with the tube 16 and bore 22 under the control of the throttle valve 15. A cleansing liquid, herein water, is adapted to be admitted under pressure to the tube 17 through a pipe connection 25 from a suitable source of supply. This water tube 17 extends coaxially through the air tube 16 and drilling motor and terminates at its free end in a longitudinally extending aperture or bore 26 formed coaxially through the drill steel 5. Herein, it will be noted that the rear end of the bore 22 in the piston 4 terminates in an enlarged bore 27 which communicates with the rear

end of the cylinder by way of a slot or groove 28 formed in the piston. It will further be noted that the drill steel 5 is adapted to be intermittently rotated by means of usual 5 ratchet and pawl mechanism, generally designated 29, carried at the rear end of the cylinder and including a forwardly extending spirally grooved rifle bar 30 which cooperates with a rifle nut 31 suitably secured with 10 in the rear end of the piston 4. The striking bar 32 of the piston is provided with straight longitudinally extending grooves or flutes 33 which cooperate with a chuck nut 34 suitably secured within the drill steel receiving chuck 6. It will be evident that when 15 the piston reciprocates it is intermittently rotated by the rifle bar and this intermittent rotation is transmitted by means of the grooves in the striking bar cooperating with the chuck nut to the chuck 6 and hence to the 20 drill steel.

In the operation of my improved mechanism it will be noted that the throttle valve 15 is manipulated by the operator admitting 25 fluid pressure to the valve mechanism 11 which distributes the pressure alternately to the passages 9 and 10 causing reciprocation of the piston 4 which actuates the drill steel 5. It will also be evident that the grooves 30 in the striking bar of the piston intermittently communicate with the forward end of the cylinder, thus permitting motive fluid to be conducted through the chamber 23 and hence to the hollow drill steel. Pressure fluid 35 is also admitted to the tubular member 16, bore 22, chamber 23, to the aperture 26 in the drill steel with which liquid cleansing fluid admitted through the tube 17 intermingles and passes to the bottom of the drill 40 hole, removing the cuttings therefrom. To supplement this cleansing fluid supply to the drill hole, I have terminated the free end of the tubular member 16 at such a distance within the bore 22 that, just previous to the 45 exhaust of the rear end of the cylinder, the forward end of the tube runs out of the bore 22, opening communication from the rear end of the cylinder to the bore 22 by way of the groove 28 and the bore 27. This causes 50 an intermittent supply of pressure fluid to the drill steel as the piston approaches the forward end of its stroke, when an increased amount of pressure fluid will flow through the bore 22 until the cylinder pressure has 55 been materially reduced by exhaust.

As a result of my improvement a drilling mechanism having improved cleansing means of a simple, compact nature is provided 60 whereby the supply of cleansing fluid through the air and water tubes is supplemented by an intermittent supply of pressure fluid controlled by the hammer piston. It will further be noted that improved cleansing means are provided which permit an intermittent supply 65 of exhaust pressure fluid from the motor

cylinder supplemental to the liquid and pressure fluid supply through the tubes thereby facilitating the drilling of deep holes. Further, it will be noted that this mechanism may be applied to a machine of standard form 70 with a minimum of change. These and other advantages of my improvement will be clearly apparent to those skilled in the art.

While I have in this application specifically described one form which my invention may assume in practice, it will be understood that this form is shown for purposes of illustration and that the invention may be modified and embodied in various other forms without departing from its spirit or the scope of 80 the appended claims.

What I claim as new and desire to secure by Letters Patent is:

1. In a drilling mechanism, a cylinder, a piston reciprocable therein, a liquid tube and a pressure fluid conducting tube for supplying cleansing fluid to a bore in a drill steel independently of the supply of piston actuating fluid to the cylinder and means provided by said piston and cooperating directly with one of said tubes for intermittently supplementing said cleansing fluid supply. 90

2. In a drilling mechanism, a cylinder, a piston reciprocable therein, means for supplying cleansing liquid and gaseous fluid to a hollow drill steel including coaxially arranged supply tubes extending within said piston, and means formed in said piston and cooperating with one of said tubes for intermittently opening communication between 95 the rear end of said cylinder and the hollow drill steel for supplementing said gaseous cleansing fluid supply. 100

3. In a drilling mechanism, a cylinder, a piston reciprocable therein and having a bore, means for supplying cleansing fluid to a hollow drill steel independently of the supply of piston actuating fluid to the cylinder including coaxially arranged tubes extending within the bore in said piston, and means formed in said piston and cooperating directly with one of said tubes for intermittently supplementing the supply of cleansing fluid through the bore in said piston. 110

4. In a drilling mechanism, a cylinder, a piston reciprocable therein having a bore, means for supplying cleansing liquid and gaseous fluid to a hollow drill steel including inner and outer supply tubes having free ends extending within the bore in said piston, the free end of the outer one of said tubes terminating within said piston, and means permitting intermittent withdrawal of the free end of the outer tube from the bore in said piston during normal operation of the latter for supplementing said gaseous cleansing fluid supply. 120

5. In a drilling mechanism, a cylinder, a piston reciprocable therein, means including inner and outer tubes for supplying liquid 130

and gaseous fluid to a bore in a drill steel, and means provided by said piston controlled by movement thereof and cooperating directly with said outer tube for intermittently supplementing said fluid supply.

5 6. In a drilling mechanism, a cylinder, a piston reciprocable therein having a bore, means for supplying cleansing liquid and gaseous fluid to a hollow drill steel comprising coaxially arranged supply tubes having free ends extending within the bore in said piston, and means permitting the intermittent withdrawal of the free end of one of said tubes from said piston during normal operation of the latter for supplementing said gaseous fluid supply.

10 7. In a drilling mechanism, a cylinder, a piston reciprocable therein providing fluid conducting means communicable with the cylinder for portions only of each piston stroke and adapted respectively to intermittently supply cleansing fluid from opposite ends of said cylinder to a hollow drill steel during normal operation thereof, and supplemental cleansing fluid supply means comprising coaxially arranged liquid and gaseous fluid supply tubes extending forwardly within said piston.

15 8. In a drilling mechanism, a cylinder, a piston reciprocable therein, means controlled by said piston for supplying cleansing fluid from the forward end of said cylinder to a hollow drill steel, means for supplying liquid and gaseous cleansing fluid to the hollow drill steel comprising coaxially arranged tubes extending within said piston, and means controlled by said piston for intermittently supplying cleansing fluid from the rear end of said cylinder to supplement said gaseous fluid supply during a part only of each forward movement of the piston.

20 9. In a drilling mechanism, a cylinder, a piston reciprocable therein, means controlled by said piston for supplying cleansing fluid from the forward end of said cylinder to a hollow drill steel, means for supplying liquid and gaseous cleansing fluid to the hollow drill steel comprising coaxially arranged tubes extending within said piston, and means controlled by cooperation between said piston and one of said tubes for intermittently supplying cleansing fluid from the rear end of said cylinder to supplement said gaseous fluid supply during a part only of each forward movement of the piston.

25 10. In a drilling mechanism, a cylinder, a piston reciprocable therein, and means for supplying cleansing fluid to a bore in a drill steel including a plurality of tubes, each connected to a continuous fluid supply, said piston having a bore therethrough for slidably receiving one of said tubes, the latter being of such length that it is positioned entirely out of said bore during a portion of the piston stroke to establish communication by way

of the piston bore between the cylinder and the drill steel bore to supplement the cleansing fluid supplied by said tubes.

11. In a drilling mechanism, a cylinder, a piston reciprocable therein and having a bore therethrough, and means for supplying cleansing fluid to a bore in a drill steel, including a tube extending into said cylinder and connected to a constant supply of gaseous fluid, said tube at its free end slidably fitting in said piston bore during a portion only of the piston stroke and said bore conducting fluid from the cylinder during the remainder of the piston stroke for supplementing the cleansing fluid supplied through said tube.

12. In a drilling mechanism, a cylinder, a piston reciprocable therein having a bore therethrough, and means for supplying cleansing fluid to a bore in a drill steel, including concentric tubes extending into said cylinder, the inner of said tubes being connected to a constant liquid supply and extending at all times through said piston bore, the outer of said tubes being connected to a constant gaseous supply and at its free end slidably fitting in the piston bore when the piston is in the rear end of the cylinder but free from said bore when the piston is in the forward end of the cylinder so that pressure actuating fluid may be intermittently supplied through the piston to supplement the cleansing fluid supplied through said tubes.

In testimony whereof I affix my signature.
